CLAIM

The ornamental design for front panel for an air conditioner, as shown and described.

DESCRIPTION

FIG. 1 is a frontal perspective view of the air conditioner front panel showing the new design;

FIG. 2 is a front elevational view thereof;

FIG. 3 is a left side elevational view thereof;

FIG. 4 is a right side elevational view thereof; and,

FIG. 5 is a top plan view thereof.

The structure depicted in broken lines in FIGS. 1, 2 and 5 has been shown for illustrative purposes only and forms no part of the claimed design.
